ABSTRACT

A non-adhesive endless belt is used for heating and fixing toner images upon a recording medium by mounting the belt on a roller having means for heating it and on a driving roller spaced apart from the heated roller means. The recording medium is passed closely adjacent to or with its toner-carrying surface in contact with the surface of the heated belt to fuse the toner in the form of the image on the recording medium. Cleaning means and a preheated pressure roller are also provided to improve the quality of the fused toner image.

DEVICE FOR HEATING AND FIXING TONER IMAGES UPON A RECORDING MEDIUM

BACKGROUND OF THE INVENTION

The present invention relates to a device for heating and fixing toner images upon a recording medium in an electrophotographic process using dry methods or a thermographic process.

Heat fixing is generally employed for fixing a visible image, for example, formed by toner containing easily fusible resin in an electrophotographic process by dry method. A heat source is employed such as an infrared ray lamp, a halogen lamp or a nichrome wire so that the visible image may be heated to a temperature between 100°C and 150°C so as to be fused. However, this method has disadvantages in that the time required for raising the temperature of the visible image to a fixing temperature is quite long; the thermal efficiency is low; and other parts of the apparatus become heated. To overcome these problems, there have been proposed various methods, but none has been particularly successful in reducing the rise time for reaching the fixing temperature and accomplishing the perfect fixing at high speed.

SUMMARY OF THE INVENTION

One of the objects of the present invention is to overcome the problems of the prior art device described above.

Another object of the present invention is to provide an arrangement in which a recording medium is not brought into direct contact with a heating means and is prevented from being over-heated.

Another object of the present invention is to provide an arrangement for preventing the toner from being adhered to an endless belt for heating the toner.

Another object of the present invention is to provide an arrangement for facilitating the easy removal of the toner adhered to the endless belt.

Another object of the present invention is to prevent overheating of the endless belt.

According to one aspect of the present invention, a non-adhesive endless belt is used for heating the toner upon a recording medium. The endless belt rides about a heating roller incorporating therein a heater and a drive roller spaced apart from the heating roller so that the endless belt may be suitably cooled by the time it returns to the heating roller after it has fused the toner on the recording medium. That is, the overheating of the endless belt may be prevented. The endless belt for heating the toner may be brought into direct contact with the recording medium or may be spaced apart therefrom by a suitable distance. Preferably a rotary cleaning brush may be positioned in contact with the endless belt for removal of the toner and other contaminants which cling to the endless belt. This arrangement is especially advantageous when the endless belt is in direct contact with the recording medium.

A device in accordance with the present invention may be used for heating a heat-sensitive substance such as, for example, a heat-sensitive paper or a stencil.

The present invention will become more apparent from the following description of the preferred embodiments taken in conjunction with the accompanying drawings.

DESCRIPTION OF THE DRAWINGS

FIG. 1 is a sectional view in elevation a fundamental heating and fusing device in accordance with the present invention;

FIGS. 2 and 3 are sectional views as in FIG. 1 illustrating additional features thereof;

FIG. 4-A and FIG. 4-B are side views illustrating the copies used in thermographic process; and

FIG. 5 is a sectional view in elevation of a device in accordance with the present invention for accomplishing the thermographic development of the copies shown in FIGS. 4-A and 4-B.

DESCRIPTION OF THE PREFERRED EMBODIMENTS

FIG. 1 illustrates the fundamental arrangement of the present invention, in which a visible image 2 is formed by a developing agent (toner) containing fusible resins upon a recording medium 1 advanced in the direction indicated by the arrow *a*. When the recording medium 1 is brought into contact with an endless belt 5 made of a non-adhesive material and it is heated by means of a hollow roller 4, over which a belt rides, incorporating therein a heater 3 such as an infrared lamp, a halogen lamp, a nichrome wire, etc. Alternatively, the roller 4 may serve as a heater. The toner is heated and fixed to the recording medium 1, so that the permanent image 8 may be formed. The endless belt 5 which wraps in it the hollow roller 4 and a spaced drive roller 6 is advanced at the same speed as that of the recording medium 1 in the direction *b*. A pressure roller 7 rotating in the direction indicated by the arrow *c* has its peripheral surface covered with an elastic member such as thermostable rubber capable of withstanding a temperature of 200°C and serves to press the toner image 2 against the endless belt 5 and to prevent the toner image from being distorted. The fixing speed of the visible image may be improved when the pressure roller 7 is pre-heated to a temperature from 60° to 90°C.

When the surface of the endless belt 5 is moved away from the heating roller 4, its temperature is lowered by cooling so that any toner attached thereto is sufficiently cooled to be easily removed from the endless roller 5. Furthermore, temperature control of the heating roller may be easily achieved.

In FIGS. 2 to 5, members which function as those in the embodiment illustrated in FIG. 1 are indicated by the same reference numerals. Therefore, the explanation of these members will not be made. In the embodiment illustrated in FIG. 2, a cleaning brush 9 rotates in the same direction with that of the roller 6 so as to clean the endless belt 5. Therefore, the endless belt 5 free from the toner may be always brought into contact with the heating roller 4.

The cleaning brush 9 is spaced apart from the heating roller 4 so that the aging of the cleaning brush 9 may be prevented. That is, the service life may be extended. As the endless belt 5 moves away from the heating roller 4, the toner attached thereupon is cooled, so that the removal of the toner upon the endless belt 5 may be further improved.

The embodiment illustrated in FIG. 3 is provided with an application roller 10 for applying silicon oil or the like over the endless belt 5 in order to form a non-

adhesive layer thereupon. The application roller 10 is coated with a permeable substance such as cloth 9' for holding silicon oil therein. The application roller 10 rotates about a shaft 11 and makes contact with the endless belt 5 so that the non-adhesive layer may be formed upon the endless belt 5. Therefore non-adhesiveness of the endless belt surface 5 may be further improved.

FIG. 4-A and FIG. 4-B are side views of a heat-sensitive substance (thermographic copy) illustrating its thermographic process. The copy is, for example, a stencil. In FIG. 4-A, reference numeral 12 designates a heat-sensitive copy made of a porous paper or plastic sheet with waxy backing; and 13, an original to be reproduced in registration with the copy 12. Infrared rays are irradiated from the back of the copy 12 so that the image (or printing) portion upon the original 13 (generally a black-colored portion) absorbs much infrared rays. The heat rays 15 irradiated from the image or printing portion 13a upon the original 12 which is heated to a high temperature by the infrared rays 15 heats a portion on the copy 12 corresponding to the image or printing portion 13a of the original 13. In consequence, wax is melted so that the porous paper or plastic sheet 12a is exposed. The infrared rays 14 incident upon a non-image portion or non-printing portion upon the original 13 are reflected and dissipated as shown by 16. Consequently, the temperature of the non-printing portion is not raised, so that a portion on the copy 12 corresponding to this non-printing portion will not melt. The reproduced copy 12 may be used as stencil in mimeographing.

The embodiment illustrated in FIG. 5 is for accomplishing the thermographic process whose principle has been explained with reference to FIG. 4-A and FIG. 4-B, by a heater in accordance with the present invention. The original 13 is placed over the copy 12 as shown and they are passed through the nip between the heating roller 4 and the pressure roller 7 in the 40

direction indicated by the arrow a. Thus, the thermographic process may be accomplished. The processing speed may be improved when the pressure roller 7 is pre-heated. The endless belt 5 serves to easily control the temperature in the thermographic process.

What is claimed is:

1. A device for heating and fixing a toner image upon a toner-carrying recording medium being transported thereby comprising:

- 10 a. a heating roller disposed adjacent the path of travel of said recording medium;
- b. an endless belt made of a thermostable substance and mounted for travel around said heating roller so as to transfer heat from said roller to the toner-carrying surface of said recording medium to fuse the toner thereon;
- c. means for driving said endless belt in the same direction as that of said recording medium; and
- d. a preheated pressure roller positioned opposite said heating roller and cooperating with said heating roller to pass said recording medium under pressure between them.

2. The device defined in claim 1 wherein said endless belt is made of a non-adhesive material.

3. The device defined in claim 1 wherein said heating roller is spaced apart from said belt-driving means.

4. The device defined in claim 1, including means for cleaning the surface of said endless belt.

5. The device defined in claim 4 wherein said cleaning means is a rotating brush.

6. The device defined in claim 1 wherein an application means is provided for applying a non-adhesive coating upon the surface of said non-adhesive endless belt.

7. The device defined in claim 6 wherein said application means is a application roller coated with a permeable substance.

8. A device as in claim 1, wherein the pressure roller has a thermostable surface.
